UNITED STATES PATENT OFFICE.

ABRAHAM B. DUNKLE, OF STEELTON, PENNSYLVANIA.

WINDOW-SHADE HOLDER.

SPECIFICATION forming part of Letters Patent No. 521,784, dated June 26, 1894.

Application filed December 31, 1892. Serial No. 456,930. (No model.)

To all whom it may concern:

Be it known that I, ABRAHAM B. DUNKLE, a citizen of the United States, residing at Steelton, in the county of Dauphin and State 5 of Pennsylvania, have invented certain new and useful Improvements in Window-Shade Holders, of which the following is a description, reference being had to the accompanying drawings, and to the letters and figures 10 of reference marked thereon.

My invention relates to an extension strip, for window shade rollers, the object being to provide a comparatively inexpensive device for the support of curtain roller brackets 15 whereby the same strip can be adapted for different sized windows and varying widths of shades.

My invention consists in the various matters hereinafter described and referred to in 20 the appended claims.

In the accompanying drawings which illustrate my invention, Figure 1 is a view in perspective of my improved window shade strip. Fig. 2 is a horizontal section through the same.

25 In the drawings A represents as a whole, the strip or bar to which the roller brackets are attached; this strip is extensible, as shown in Fig. 1, and is composed as herein shown of two parts a' a', each being cut away for about 30 half its thickness between the points 1 and 2 so that when placed together the parts a' will lap, and together, in thickness just equal the thickness of the main body of the strip. These parts are secured to each other and 35 guided one upon the other by means of bands of tin or other suitable metal, one of said bands c, being secured to the end of the lapping part of each section and partially or wholly encircling the other section. By this 40 means the sections are permitted to slide apart a limited distance, the bands c, forming stops to prevent their separation. At a short distance from the outer end of each section a vertical recess d is cut, these recesses being 45 adapted to receive the shanks e of the bracket f. By making this recess entirely within the body of the strip an outer wall for the recess d is formed, and through this part of the strip outside the recesses, nails or other securing 50 means may be driven to fasten the strip in place.

In order to hold the shank of the roller bracket in place I have herein shown an angle plate of zinc, tin or other suitable metal, this plate g being secured to the strip

and extended out over the recesses so as to 55 hold the shanks of the bracket.

It will at once be seen that a strip constructed in accordance with the present invention possesses many advantages. Especially is this true in the manufacture, as the 60 recess d necessitates but a cut of a machine, and, this recess being formed wholly within the strip as shown, a back and sides are formed for holding the bracket in place, thus necessitating in addition, but a support for the 65 bottom and front of the bracket. This is supplied by the angle plate g, which, being of tin or zinc as described, is sufficiently resiliency to clamp the bracket and aid by its 70 resiliency in holding said bracket in place.

The device is extremely simple and efficient. The recess or groove is formed in the strip at a single cut, but two parts (the strip and the angle plate) are required, and when these are assembled as shown, a chamber is formed 75 into which the bracket is readily inserted and as readily removed, and in which it is firmly held, while the portion of the strip between the end thereof and the recess, affords a surface through which a tack may be driven to 80 hold the strip in place.

Having thus described my invention, what I claim as new, and desire to secure by Letters Patent, is—

1. A support for brackets and the like comprising a strip provided with a groove formed therein, the sides of said groove from the back to the front lying in the same line, and a separate plate fitting partly over said groove; substantially as described. 85

2. A support for brackets and the like comprising a strip provided with a groove formed therein and extending to the lower edge thereof, and a separate plate fitting partly over said groove; substantially as described. 90

3. A support for brackets and the like comprising a strip provided with a groove formed therein and extending to the lower edge thereof, and a separate angle plate fitting partly over the face of said groove and extending 100 beneath the same whereby the bracket is held in place; substantially as described.

In testimony whereof I affix my signature in presence of two witnesses.

ABRAHAM B. DUNKLE.
